UNITED STATES PATENT OFFICE.

VICTOR H. JENNINGS, OF WORCESTER, MASSACHUSETTS, ASSIGNOR TO MILLS WOVEN CARTRIDGE BELT COMPANY, OF WORCESTER, MASSACHUSETTS, A CORPORATION OF MASSACHUSETTS.

TUBULAR WOVEN FABRIC WITH WIDENING.

1,129,037.

Specification of Letters Patent. Patented Feb. 16, 1915.

Original application filed July 20, 1911, Serial No. 639,635. Divided and this application filed April 8, 1912. Serial No. 689,209.

To all whom it may concern:

Be it known that I, VICTOR H. JENNINGS, a citizen of the United States, residing at Worcester, in the county of Worcester, State of Massachusetts, have invented a certain new and useful Improvement in Tubular Woven Fabric with Widening, of which the following is a specification, reference being had therein to the accompanying drawings.

The invention claimed herein is a division of that of my application for Letters Patent for sheath or scabbard filed July 20, 1911, Serial No. 639,635 on which Letters Patent were issued under date of August 25, 1914, No. 1,108,864.

The invention consists in a seamless tubular web or fabric having one section of its length woven as a tube of a given diameter, and an adjoining tubular section continuous with the first and of equal width therewith as produced in the loom and woven with a longitudinal fold or plait in the form of a transverse return bend which enables such second section to be enlarged by expanding or stretching it so as to straighten out the material included in the fold or plait.

A web or fabric woven in conformity with the invention, and a convenient fabric-structure for the same, are illustrated in the drawings, in which latter—

Figure 1 is an elevation of a length of the said web or fabric. Fig. 2 is a top view of the upper end of such length. Fig. 3 is a top view thereof showing the said end partly expanded. Fig. 4 is a diagram illustrating the fabric-structure of the intermediate sections of the web or fabric. Fig. 5 is a diagram illustrating the fabric-structure of the sections which are formed with the integral widening.

The web or fabric shown and described herein is woven in a flattened state.

Having reference to the drawings, the web or fabric shown comprises a section 1 of a given diameter, which section is or may be of ordinary tubular weave, and a section 2 of tubular weave having the integral widening portion 3 in the form of a transverse return bend. The said widening portion comprises two additional plies of fab-

ric woven intermediate the main portions of the tube, and which are so conjoined transversely with the adjoining portions 55 of section 2, and with each other, that they form a longitudinal fold or plait in such section. Thus, whereas in section 1 as herein illustrated there are two plies constituting the opposite side-portions of the flat 60 tened tube, there are in section 2 four superimposed plies in a cross-section passing transversely through the longitudinal fold or plait.

A convenient fabric-structure is indicated 65 in Figs. 4 and 5. Section 1 is woven in the usual way of weaving tubular or hose-pipe web-structure in flat form. Fig. 4 will serve to illustrate the fabric-structure of the same. Thus, starting at the left hand side, the first pick of weft extends from the point a at the said side through a shed in the warp-threads of the lower ply to the right hand side at a' . The second pick of weft extends from the right hand side 70 through a shed in the warp-threads of the upper ply to the left hand side at a^2 . The third pick extends from left to right through a second shed in the warp-threads 75 of the lower ply. The fourth pick extends from right to left through a second shed in the warp-threads of the upper ply to the point a^3 . The picks and sheds are repeated in the order given. Fig. 5 will serve 80 to illustrate the fabric-structure for the section 2. Thus, starting at the left hand side, the first pick of weft extends through a shed in the warp-threads of the bottom ply of section 2 to the right hand side at b' . The second pick of weft extends from the 85 right hand side through a shed in the right hand portion of the warp-threads of the top ply of section 2 to an intermediate point at b^2 , and continues through a shed in the lower ply of the plait to the point b^3 . The 90 third pick of weft extends from left to right through a shed in the warp-threads of the upper ply of the plait to a point at b^4 immediately alongside point b^2 . The 95 fourth pick of weft extends from point b^4 through a shed in the left hand portion of the warp-threads of the top ply of section 2 to the left hand side at b^5 . The fifth pick of weft extends to the right hand side 100

through a second shed in the warp-threads of the bottom ply. The sixth pick extends from the right hand side through a second shed in the right hand portion of the warp-threads of the top ply of section 2 to the point b^2 , and in the lower ply of the plait, to the point b^3 . The seventh pick extends from left to right through a second shed in the warp-threads of the upper ply of the plait to the point b^4 . The eighth pick extends from the point b^4 to the left through a second shed in the left hand portion of the warp-threads of the top ply to the point b^5 . The picks and shedding are repeated in the order given. The sections 1 and 2 are woven in an alternating succession so as to produce a web of continuous tubular structure in which such sections are repeated a number of times. The warp-threads used in weaving the plait 3 are floated from one section 2 to the next, as indicated by dotted lines in Fig. 1. The completed web is cut up into lengths, each comprising a section 1 and a section 2, and the floated warp-threads are cut away. The location of the plait may vary transversely of the web or fabric, and may be woven either inside or outside the tube. After the web has been cut across through the section 2, as in severing the continuous web into lengths, the section 2 may be expanded or enlarged by spreading the same so as to straighten out the plait more or less completely, as in Fig. 3. I am thereby enabled to produce a sheath or the like of seamless tubular fabric-structure of greater diameter in its upper portion than in its lower portion, and which may be caused to flare outwardly and upwardly in its widened portion. Stitches or other fastenings applied to the plait will serve to hold the section 2 in its expanded

and flared form, as in the application previously mentioned herein.

A widening produced in the manner herein explained has the special advantage that the fabric of the tube has, or may have, everywhere the same number of warp-threads and weft-threads to the square inch. In such case no difference in character or closeness of texture is apparent in section 2 at or adjacent the widening.

A special characteristic of the widening forming a feature of my invention is the fact that it is open at its ends, thereby facilitating the operation of sliding one portion of a plait or fold over upon another in adjusting the widening to the required dimensions. This also facilitates giving the required flared or tapering form to the expanded part of the sheath or the like in which the fabric is embodied.

What is claimed is:—

A seamless continuously-tubular fabric having a section of its length woven as a tube of a given diameter, and an adjoining section of equal width with the first as produced in the loom woven with an integral widening in the form of a longitudinal fold or plait open at its opposite ends and forming an open-ended transverse return bend which enables such second section to be given the form of a flared widening with the material included in the fold or plait in a more or less straightened out condition, with the extent of remaining overlap varied in the length of the widening.

In testimony whereof I affix my signature in presence of two witnesses.

VICTOR H. JENNINGS.
